UNITED STATES PATENT OFFICE.

LUCIAN BIRDLEBOUGH, OF TAYLOR, NEW YORK.

FOLDING MANGER.

SPECIFICATION forming part of Letters Patent No. 288,917, dated November 20, 1883.

Application filed June 7, 1883. (No model.)

To all whom it may concern:

Be it known that I, LUCIAN BIRDLEBOUGH, a citizen of the United States, residing at Taylor, in the county of Cortland and State of New York, have invented certain new and useful Improvements in Folding Mangers and Feed-Boxes, of which the following is a specification, reference being had therein to the accompanying drawings.

10 My invention relates to a combined feed-box and manger adapted for service in stalls where cows, sheep, or other animals are confined by stanchions; and the novelty consists in the construction, arrangement, and adaptation of 15 parts, as will be more fully hereinafter set forth, and specifically pointed out in the claim.

10 The object of the invention is to provide a feed-box or series of feed-boxes in a hinged structure, a hinged cover of which will serve as a guard to prevent waste of food, and the whole structure being hinged to the floor, and adapted, when turned up, to serve as one side of a manger, the whole being simple, inexpensive of manufacture, and efficient in service.

20 The invention is fully illustrated in the accompanying drawings, which form a part of this specification, and in which—

30 Figure 1 is a perspective view of my invention; Fig. 2, a top plan view; and Fig. 3, an end elevation, partly in section, showing the box raised to form a manger in dotted lines.

35 Referring to the drawings, similar letters of reference indicate like parts in all the figures.

A indicates the row of stanchions of ordinary construction, and B the floor of a stable. Hinged to the floor at C is a box, D, having a hinged cover, E, and a series of feed-boxes, e. 40 The box D is of any approved material and construction, and is adapted to fit snugly between the hinge-points C and the row of stanchions. Working in a transverse slot, f,

is an arm, g, of a bolt, G, which bolt reciprocates in guides g' on the under face of said cover E, and is adapted to hold the cover rigidly open when one end is inserted in the recess h', formed in a transverse partition of the box, or closed and locked when the opposite end is engaged in the recess h' in the front side of the box. The slot f in the cover has a side recess, f', in which the arm g may be forced to lock the bolt G in its engagement with the recess h'.

45 I indicate a box adapted to contain salt. 55 This box is arranged to utilize the space between the feed-boxes, and it has a sliding cover, i. When the cover E is elevated, the said cover i is within the reach of the cattle, and to prevent its being opened by them the 60 bolt G at such time securely locks it against displacement.

50 It will be observed that when the feed-boxes are in use the cover E serves as a guard to prevent scattering of the grain, meal, or other food, and that the bolt G holds the salt-box in a closed and locked condition, and that when the entire box structure is turned on its hinges a distance of ninety degrees it serves as a guard to keep hay, stalks, and other fodder 70 within the reach of the animals.

Having thus described my invention, what I claim as new, and desire to secure by Letters Patent, is—

75 The combination, with the box D, having a series of feed-boxes and an intervening salt-box, I, with sliding cover i, of the bolt G, operating in the hinged cover E, and adapted to simultaneously hold said cover E open and the sliding cover i closed, as set forth. 80

In testimony whereof I affix my signature in presence of two witnesses.

LUCIAN BIRDLEBOUGH.
